(57) **CLAIM**

Applicant claims the ornamental design of a chair, as shown and described.

DESCRIPTION

FIG. 1 is a perspective view of a chair embodying the concepts of the present design invention;

FIG. 2 is a front elevational view of the chair of FIG. 1;

FIG. 3 is a rear elevational view of the chair of FIG. 1;

FIG. 4 is a right side elevational view of the chair of FIG. 1;

FIG. 5 is a left side elevational view of the chair of FIG. 1;

FIG. 6 is a top plan view of the chair of FIG. 1; and,

FIG. 7 is a bottom plan view of the chair of FIG. 1.

The broken lines in any of the above views are for environmental purposes only and form no part of the claimed design invention.
